(57) **CLAIM**

We claim the ornamental design for a sticker pad, as shown and described.

DESCRIPTION

FIG. 1 is a front view of the sticker pad of the present invention in an open position.

FIG. 2 is a rear view thereof.

FIG. 3 is a front perspective view thereof.

FIG. 4 is another front perspective view of the sticker pad in another open position.

FIG. 5 is a bottom view of the sticker pad in another open position.

FIG. 6 is a top view thereof.

FIG. 7 is another front perspective view of the sticker pad in another open position with varying broken line elements; and,

FIG. 8 is another rear view of the sticker pad in a closed position.

The broken lines in the figures represent portions of the sticker pad that form no part of the claimed design.

1 Claim, 8 Drawing Sheets
